FIG. 1 is a top plan view of a toy fork lift vehicle showing my new design.

FIG. 2 is a left side elevational view thereof.

FIG. 3 is a front elevational view thereof shown on a slightly enlarged scale.

FIG. 4 is a rear elevational view thereof.

The right side elevational view is substantially a mirror image of what is shown in FIG. 4. The undisclosed bottom of the design is substantially plain and unornamented.
